Attorney

UNITED STATES PATENT OFFICE.

WILLIAM H. FULLINGTON, OF CLEVELAND, OHIO, ASSIGNOR TO THE SUPERIOR MANUFACTURING COMPANY, OF CLEVELAND, OHIO, A CORPORATION OF OHIO.

HAND ROPE-MAKING MACHINE.

Application filed February 16, 1920, Serial No. 358,861. Renewed August 9, 1922. Serial No. 580,806.

To all whom it may concern:

Be it known that I, WILLIAM H. FULLINGTON, a citizen of the United States, and resident of Cleveland, in the county of 5 Cuyahoga and State of Ohio, have invented certain new and useful Improvements in Hand Rope-Making Machines, of which I hereby declare the following to be a full, clear, and exact description, such as will 10 enable others skilled in the art to which it appertains to make and use the same.

The objects of the invention are to improve the operating qualities of a rope twisting machine, and it is exemplified in the 15 mechanism required for making the double or "hawser" twist in constructing a rope or hawser.

The particular objects are to improve the holding qualities of the "spreader" by means 20 of which the angle of winding is determined, and also to improve the working qualities of the swivelled hook by means of which the hawser is held under tension during the twisting operation.

25 The machine illustrated is operated by hand but the mechanism can also be operated by power if desired. The invention is hereinafter more fully described, shown in the accompanying drawings and specifically 30 pointed out in the claims.

In the accompanying drawings Fig. 1 is a perspective of the mechanism required to perform the work; Fig. 2 is a front view of the twisting device, one half of the cover 35 being removed to show the gearing; Fig. 3 is a vertical central section therethrough; Fig. 4 is a front elevation of the spreading device; Fig. 5 is a rear elevation thereof; Fig. 6 is a central vertical section thereof; 40 Fig. 7 is a longitudinal section of the swivelled hook which holds the twisted extremity of the hawser.

In these views, A is the twister body. In this body are assembled the rotatable hooks 45 B, B, to which the looped ends of the loose strands to be twisted are attached, C is a shaft upon which a main spur gear D is secured, which rotates the pinions E, E, secured to the shafts F, F of the aforesaid 50 hooks. A crank G or other power communicating means, may be attached to the shaft C.

The rear extremity of the hawser is sup-

ported by means of a swivelled hook H, which is held under constant tension by means of 55 the weight I and rope and pulley J and K respectively. To separate the loose strands while they are being twisted and to wind them in the hawser at the required angle, a spreader L is employed of the peculiar disc 60 form shown in Figs. 4, 5 and 6. Here M, M, are spaced radial openings in the periphery of the disc, their adjacent walls having overhanging and slightly re-entrant or inwardly turned T-shaped flanges N, N, which retain 65 the loose strands and prevent them from slipping out of the spacer while the twisting operation is progressing.

The body of the spacer is conical at O to serve as a guide to the strands. Since the 70 swivelled hook H must revolve rapidly as the hawser twists, it is supplied with a ball or friction bearing P and balls Q, enclosed in a sleeve R, to which a holding eye S is attached.

75 This method of constructing the ball bearing P for the swivelled hook prevents dust or lint from entering the ball bearing, and preventing the free rotation of the hook. The bearing P forms a closure for the open 80 end of the sleeve R. The hooks B are preferably inserted in the collars or couplings F' and the shafts F are secured detachably thereto by means of set screws F², thus making hooks of all sizes interchangeable 85 and making it possible to manufacture a large variety of sizes of hawser cords or ropes on the same machine. It also permits the movements of the parts to be accurately controlled. The hooks are secured to the 90 couplings by means of set screws, F³. The gear case of the twisting device is formed in the form of a hollow disc like shell showing great rigidity and lightness of construction.

The case comprises a back A and a marginal 95 flange A' and the bearings for the several shafts are formed in integral bosses A². The front is enclosed by means of a cover, A³, which serves also as a retaining means for the gears, and protects the operator from 100 injury. The parts are secured together by locking bolt.

Having described the invention, what I claim as new and desire to secure by Letters Patent is:

1. In a twisting machine, a disc-like spacer

- provided with radial circumferential openings, the walls of said openings having overhanging and inwardly curved outer extremities.
5. 2. In a twisting machine, a disc like spacer, said spacer provided with radial circumferential openings, the adjacent outer sides of said openings extending towards

each other and inwardly curved, substantially as and for the purpose set forth. 10

In testimony whereof, I hereunto set my hand this 22nd day of January 1920.

WILLIAM H. FULLINGTON.

In presence of:—

W.M. M. MANSON,
S. W. SANGSTER.
